[57] CLAIM

The ornamental design for a “watch casing and bezel”, as shown and described.

DESCRIPTION

FIG. 1 is a perspective view of a watch casing and bezel showing my new design;

FIG. 2 is a left side elevational view thereof;

FIG. 3 is a top plan view thereof;

FIG. 4 is a right side elevational view thereof;

FIG. 5 is a front elevational view thereof;

FIG. 6 is a rear elevational view thereof;

FIG. 7 is a bottom plan view thereof; and,

FIG. 8 is a perspective view of a watch casing and bezel in accordance with a second embodiment of my invention.

The left and right side elevational views, the top and bottom plan views, and the front and rear elevational views of the second embodiment are similar to those respective views illustrated in FIGS. 2-7 wherein in the second embodiment, the side button would be depicted in broken lines.

The broken-lines showing a portion of a watch form no part of the claimed design.
